(57) CLAIM

The ornamental design for an extension link for vehicle cup holder cell phone mount, as shown and described.

DESCRIPTION

FIG. 1 is a perspective view of the extension link for vehicle cup holder cell phone mount showing my new design, wherein the extension link is mounted to a vehicle cup holder cell phone mount;

FIG. 2 is another perspective view thereof;

FIG. 3 is a first side view thereof;

FIG. 4 is a second view thereof;

FIG. 5 is a third view thereof;

FIG. 6 is a fourth view thereof;

FIG. 7 is a top view thereof;

FIG. 8 is a bottom view thereof;

FIG. 9 is a sectional view taken along line 9-9 of FIG. 4; FIG. 10 is a sectional view taken along line 10-10 of FIG. 4;

FIG. 11 is a sectional view taken along line 11-11 of FIG. 6; and,

FIG. 12 is a sectional view taken along line 12-12 of FIG. 6.

The broken lines shown illustrate environment that forms no part of the claimed design.

1 Claim, 3 Drawing Sheets
